DANIEL R. BARR, OF GRAND RAPIDS, OHIO, ASSIGNOR TO TAYLOR INSTRUMENT COMPANIES, OF ROCHESTER, NEW YORK, A CORPORATION OF NEW YORK

BAROMETER FOR USE IN CONNECTION WITH DIAGNOSTIC WORK

Application filed April 25, 1928. Serial No. 272,686.

This invention relates to improvements in barometers for use in connection with diagnostic work.

In examinations for basal metabolism, it is necessary to reduce volumes of air at an observed pressure and an observed temperature to the corresponding volumes at standard conditions, usually 0° C. (temp.), 760 mm. (pressure) and 80% aqueous vapor saturation.

It is common practice to provide tables for facilitating the reduction of observed values of volumes at observed conditions of pressure and temperature to standard conditions.

The present invention has for its object to simplify not only the use of the table, but also the observations to be made.

Another object is a barometer which aside from its usual pressure scale contains indicia and mechanism for translating the pressure indicated together with other values observed into terms of standard conditions.

For a full explanation of the invention, reference is made to the drawings, wherein:

Fig. 1 is a face view of a barometer embodying the invention;

Fig. 2 is an enlarged view of a part thereof; and

Fig. 3 is a similar view, on a smaller scale, of another form of the invention.

The barometer mechanism may be of any well known construction enclosed in the casting 1 and including a pointer 2 co-operating with a scale 5 graduated to indicate atmospheric pressure.

For the purpose of the invention, in agreement with the medical practice in this respect, the pressure is indicated in millimeters of mercury.

The pressure is marked along the periphery of the dial 3, as indicated by the numbers 640, 645, 650 and 655 . . . 780.

In radial alignment with each number is a column of figures. Concentrically with the arbor of the instrument, but independently of it, preferably on the glass cover, is mounted a hand 4, which may be turned by means of a knurled nut 4a or the like to any desired position on the dial. On the hand 4 are marked in superposition numbers consecu-

tively varying from about 15-37. There are as many numbers on this hand as there are figures in each of the radial rows in alignment with the pressure indications. In the particular instance, there are twelve numbers on the hand and twelve numbers in each radial row on the dial.

The numbers in the radial columns on the dial signify numbers of calories per liter of oxygen. One liter of oxygen at 0° C. and 760 mm. pressure is assumed, when inhaled, to have a calorific value of 4.85 cal. The physician calculates the volume of oxygen inhaled per hour and he must multiply this volume, expressed in liters, by a factor corresponding to the factor 4.85. This factor, however, is ordinarily smaller than 4.85 since the barometric pressure at altitudes higher than sea level is usually lower than 760 mm. and the temperature is usually higher than 0. The numbers in the radial columns on the dial represent the calorific values of 1 liter of oxygen at different temperatures and different barometric pressures. Each number represents the calorific value a liter of oxygen at a definite temperature and a definite barometric pressure would have at 0° C. and 760 mm. pressure. The definite temperature referred to is that number on the hand 4, which lies on the same circle as the number in question and the definite pressure is the pressure indication on the scale radially outwardly from the column containing the number in question. Each number represents the calorific value of 1 liter of oxygen measured at a known temperature and known pressure, when reduced to standard conditions.

The operation and significance of the arrangement are as follows:

The physician or other operator moves the hand 4 into alignment with the pointer 2 or rather into juxtaposition of the radial row nearest to the pointer and notes the number in lateral alignment with a selected one of the numbers on the hand 4. These numbers denote temperatures of respiratory contents in a spirometer chamber which does not form a part of this invention. The operator, at the time of operating the hand 4, consults the thermometer usually attached to the spirom-

eter and then makes the reading on the dial 3, as mentioned. Assume that the temperature is 19 and the pointer stands at 699 as indicated in Fig. 2. The hand 4 is moved to 5 the position indicated so that the numbers on the hand are directly adjacent to the numbers in the radial row in alignment with the pressure indication 700. The number 4.08 is the number adjacent to the number 19 on 10 the hand 4 and this number 4.08 is the number sought.

In the particular instance, the calorific equivalent of one liter of oxygen at 19° C., 700 mm. pressure and any relative humidity 15 combined with factors for reduction of volume to 0° C. mm., 760 mm. pressure and 80% aqueous vapor saturation.

It is understood that the figures of the radial rows represent, in general, correction 20 factors including the reduction of the volume of oxygen at any observed pressure and temperature to the volume corresponding to standard conditions of pressure and temperature.

25 The hand 4 is preferably of transparent material such as celluloid to facilitate visual juxtaposition of the numbers on the hand and the numbers on the dial.

In Fig. 3, the dial is the same as in Fig. 1, 30 but in place of the hand 4, a disk 6 is mounted for pivotal movement. The disk 6 is provided with a slit 7 on one or both sides of which are marked the numbers 15-37.

I claim:

25 1. In a barometric device, the combination with a pointer, of a dial for the pointer having along its periphery a set of barometric pressure indications corresponding to different positions of the pointer and having inwardly of each of said pressure indications a radial group of diagnostic indicia, a member pivotally mounted concentrically with the pointer and the dial and bearing temperature indicia in radial alignment for correlation 40 with the said diagnostic indicia, and means for moving the said member and the dial relatively to one another.

2. In a barometric device, the combination with a pointer, of a dial for the pointer having along its periphery a set of barometric pressure indications corresponding to different positions of the pointer and having inwardly of each pressure indication a radial group of diagnostic indicia, a hand pivotally mounted concentrically with the pointer and the dial and bearing temperature indicia in radial alignment for correlation with the 45 said diagnostic indicia, and means for moving the hand about its pivot.

60 In testimony whereof I affix my signature.
DANIEL R. BARR.
